UNITED STATES PATENT OFFICE.

FRANK L. GROVES, OF BUTTE, MONTANA.

INTERNAL-COMBUSTION TURBINE.

1,299,330.

Specification of Letters Patent.

Patented Apr. 1, 1919.

Application filed March 10, 1916. Serial No. 83,397.

To all whom it may concern:

Be it known that I, FRANK L. GROVES, a citizen of the United States, residing at Butte, in the county of Silverbow and State 5 of Montana, have invented new and useful Improvements in Internal-Combustion Turbines, of which the following is a specification.

This invention is an improved internal 10 combustion turbine motor.

One object of the invention is to effect improvements in the construction of the chamber in which the explosive mixture is generated and then exploded.

15 Another object is to improve the construction of the stator or casing and provide the same with a water jacket to prevent excessive heating and with an air chamber to supply the mixing and exploding chamber with 20 a compressed charge.

Another object is to effect improvements in the construction of the discharge valve and in the means for operating the same.

Another object is to provide a pump for 25 supplying the liquid hydrocarbon fuel to the mixing and exploding chamber.

Another object is to provide a pump to supply water to the mixing and exploding chamber.

30 Another object is to provide means for automatically operating the fuel and water pumps.

With the above and other objects in view the invention consists in the construction, 35 combination and arrangement of devices hereinafter described and claimed.

In the accompanying drawings:—

Figure 1 is a side elevation of an internal combustion turbine motor constructed and 40 arranged in accordance with my invention.

Fig. 2 is a detail longitudinal sectional view of the same on a larger scale.

Fig. 3 is a transverse sectional view of the same on the plane indicated by the line *a—a* 45 of Fig. 1.

Fig. 4 is a detailed sectional view of a fuel supply pump and its connections.

Fig. 5 is a detailed elevation, partly in section, showing one of the thrust rods of 50 the air valves and its actuating cam shaft.

Fig. 6 is a detailed elevation of one of the discharge valves and its connections.

Fig. 7 is a similar view of the same at right-angles to Fig. 6 and partly in section.

In the embodiment of my invention I provide a stator or casing which is circular in form and is here shown as comprising a peripheral member 2 and a pair of circular heads 3 which are bolted as at 4 to annular flange walls 5 which extend inwardly from the member 2 and between which is formed an annular channel 6. On the lower side of the member 2 are supporting legs 7 which are secured on cross bars 8 which connect the bases 9 of a pair of standards 10 which are arranged at opposite sides of the stator or casing and appropriately spaced therefrom and are provided near their upper ends with bearings 11 which are concentric with the stator and in which bearings a shaft 12 is mounted for rotation. A rotor 13 is keyed or otherwise secured to the shaft and is arranged in the stator and with its widened rim or peripheral portion 14 in the channel 6. This peripheral portion of the rotor is provided in its outer side with an annular channel 15 and with peripheral vanes 17. In the channel 6 of the stator are vanes 19 which are arranged reversely to the turbine vanes 17.

The peripheral member 2 is hollow and is provided with an interiorly arranged wall 20 which has a circular portion 21 concentric with and spaced from the ring 18 and also has outwardly projecting cylindrical portions 22 which are appropriately spaced apart. Thereby a water jacket or chamber 23 is formed within the wall 20 and its members 22 and an air chamber 24 for the reception of compressed air, is formed without said wall 20 and around said cylindrical members 22. Each cylindrical member 22 has a head 25 at its outer end to which is attached the outer, open end of a radially arranged mixing and combustion or exploding chamber 26. Any suitable number of these mixing and exploding chambers may be provided and preferably they are arranged in pairs diametrically opposite each other. Six of said mixing and explod- 100

ing chambers are here indicated. Each mixing and exploding chamber or cylinder has its inner end 27 secured to the ring 18 and provided with an obliquely arranged 5 nozzle or discharge passage 28, which extends also through the abutment ring. Each nozzle or passage 28 has an enlarged portion 29 near its inner end, forming a chamber for the reception and operation of a discharge valve 30 which is pivotally mounted at one side as at 31 and which closes outwardly against a seat or stop 32. The pivot of each discharge valve is formed by a shaft 33 which has a non-circular portion 10 34 that fits in and passes through a correspondingly shaped bore in the pivotal side of the valve. The discharge valves are here shown as of rectangular form but may be of any suitable shape and may be also of any 15 suitable size. Each valve 29 has an operating arm 35 at one end of its shaft 33. A lever 36 is associated with the arm 35 of each discharge valve and is pivotally mounted on a stub shaft or arbor 37 which projects from one side of the stator. A spring 38 is coiled around the arbor and has one end 39 arranged to bear on the lever and the other end 40 connected to the stator and said spring is also provided with a torsion head 20 41 by means of which it may be adjusted to increase or diminish its tension on the lever as may be desired. The lever has a camming roller 42 at its free end which bears on the arm 35. The spring, lever and arm 25 35 coact to keep the discharge valve 29 normally closed as will be understood but the spring permits the partial opening of the valve when a predetermined pressure in the mixing and exploding cylinder or chamber 30 35 is reached. When the valve is closed the valve arm 35 and the lever 36 are substantially at right angles to each other. When the valve is open the said arm and lever are nearly parallel as indicated in dotted 40 45 lines in Fig. 6 and as will be understood. To hold the lever in open position against the tension of the spring a hook dog 43 is provided which is pivotally mounted as at 44 and has an outstanding arm 45. The 50 hook of the dog engages under the arm 35 when the valve is in fully opened position and serves to hold the same in such position. To release the dog from the arm and permit the closing of the valve by the spring I provide a thrust rod 46 for each discharge valve, said thrust rod being radially arranged and adapted to travel in a guide 47.

In the center of the head 25 of each mixing and exploding chamber or cylinder is a 60 suitable spark plug 48. Each head 25 has an air inlet opening 49 to permit the passage of compressed air from the chamber 24 into said mixing and exploding chamber or cylinder. A valve 50 to close said opening

is provided and has an outwardly extending 65 stem 51 on which is a spring 52 to normally close the air valve and at the outer end of the stem is a head 53. A lever 54 is associated with each air valve to open the same against the tension of its spring. Said lever 70 is pivotally mounted as at 55 on a standard 56 which projects from a closure head 57 and a thrust rod 58 is also provided, to actuate said lever and cause the latter to open the air valve, said thrust rod being arranged 75 radially of the stator, and in guides 59.

A fuel supply pump 60 and a water supply pump 61 are also provided for each mixing and exploding chamber or cylinder 26. The fuel supply pump has a body 62 arranged radially in an opening in the head 25 and provided with a cylindrical bore 63 in which operates a plunger 64, the body being also provided with a fuel supply duct 65 which leads to the inner end of said bore 85 and with a discharge duct 66 leading from said bore to the chamber 26 and formed with a conical seat 77 in which operates a conical valve 68. A check valve 69 is provided in that portion of the duct 65 which communicates with the bore 63. The plunger has an outstanding stem or rod 70 at the outer end of which is a head 71. A spring 72 is provided which is here shown as coiled on the stem or rod and which acts to move 95 the plunger outwardly. A pipe 73 leads from a suitable fuel tank or reservoir to the duct 65. The water pump 61 is similar in construction to the fuel pump, the stem 74 of a plunger has a spring 75 to move its 100 plunger outwardly and also has a head 76. A lever 77 is provided to operate and impart pumping strokes to the plungers of the fuel and water pumps of each compressing and exploding cylinder or chamber. Said lever is pivotally mounted in the standard 105 56 as at 78 and has at its inner end a cross arm 79 which bears on the heads of the stems of said plungers. Associated with each lever 77, to operate the same and cause 110 it to impart pumping strokes to the plungers of the fuel and water pumps is a radially arranged thrust rod 80 which operates in guides 81.

A shaft 82 is provided for each mixing 115 and exploding chamber or cylinder. The said shafts are mounted in bearings 84 and are arranged parallel with and concentric to the rotor shaft 12. The rotor shaft has a long pinion 85 and each shaft 82 has a 120 gear wheel 86 which engages said pinion so that said shafts are geared to and driven by the rotor shaft and preferably the gears are so proportioned as to cause each shaft 82 to make one half of a rotation during 125 each rotation of the rotor but the gears might be otherwise proportioned if it be desired to cause the shafts 82 to rotate at

different rates of speed. Each shaft 82 has a pair of oppositely extending cams 87 which serve to operate the thrust rod 58 and to hence open the air valve 50 twice at each 5 rotation of the shaft 82. Said shaft also has a cam 88 to operate the thrust rod 80 and hence also the fuel and water pumps once during each rotation of each shaft 82. A cam 89 is also provided on said shaft to operate the thrust rod 46 and hence cause the latter to release the dog 43 from the arm 35 of the discharge valve 29 once during each rotation of said shaft 82.

Each spark plug has an electric circuit 15 including a circuit closer 90 one member of which is a cam 91 on the shaft 82 so that the spark plug is caused to produce a spark to ignite a charge in the cylinder or chamber 26 once during each rotation of the shaft 20 82. An air compressing pump to supply the chamber 24 with compressed air, preferably at a pressure of about one hundred pounds to the square inch is indicated at 92, its piston or plunger rod 93 being driven by a 25 crank 94 on the shaft 12 and a pitman 95. Any suitable means may be employed within the scope of my invention to operate the air compressing pump.

The operation of my improved internal 30 combustion turbine motor is as follows:

The cams 87, 88, 89 are arranged so that a valve 29 will be closed and held in closed position by the spring 38 while the valve 50 is opened to admit compressed air to the 35 chamber or cylinder 26 and the pumps are being operated to supply water and kerosene oil or other liquid hydrocarbon to said chamber and hence produces an explosive charge and secure compression of such charge.

40 When the pressure of the charge exceeds the resistance of the spring 38 the valve 29 opens and is held in open position by the engagement of the hook dog with the arm 35 and at this instant, the air valve 50 having closed 45 the electric circuit is closed at 91 and a spark produced by the spark plug, thus igniting the charge and causing the same to explode.

Owing to the oblique arrangement of the 50 passage 28 the exploding charge is caused to impinge on the banes of the rotor and against those of the ring 18 and hence the rotor is rotated, the charge escaping through an exhaust opening 96. Owing to the provision of the double cam 87 the air valve is

55 opened the second time, and immediately after the explosion of the charge, so that a scavenging charge of compressed air is caused to pass through the chamber 26 and passage 28 and between the rotor and ring 60 18 and out through the exhaust port 96, thus clearing out particles of carbon.

By the provision of the pump to supply a small quantity of water to the mixture the explosive properties of the mixture are in-

creased and the moisture thus produced aids 65 greatly in the elimination of the carbon particles from the walls of the chamber 26 and passage 28.

In practice two oppositely arranged cylinders are preferably exploded simultaneously, then the next pair, and then the next in rotation, according to the number of cylinders with which the rotor is provided. Any suitable number of cylinders may be employed, as will be understood.

Having thus described my invention what I claim is:—

1. In an internal combustion motor, a rotor, a stator, an explosion chamber having an air intake port and also having a discharge passage directed through the stator and to the rotor, a compressed air chamber with which the air intake port of the explosion chamber communicates, means to supply the compressed air chamber with compressed air, a valve coacting with said port to admit air to the explosion chamber, a fuel pump, to supply fuel to the explosion chamber for mixture with the compressed air to form an explosive charge, a discharge valve in the duct leading from the explosion chamber to the working face of the rotor and means including a rotor driven shaft having cams to respectively operate the air admitting valve, the fuel pump, and the discharge valve, and to cause said air valve to open both prior and subsequent to an explosion.

2. In an internal combustion motor, a rotor, a stator, an explosion chamber having an air intake port and also having a discharge passage directed through the stator and to the rotor, a compressed air chamber with which the air intake port of the explosion chamber communicates, means to supply said compressed air chamber with compressed air, a valve coacting with said port to admit air to the explosion chamber, means independent of said air valve and port to supply fuel to the explosion chamber for mixture with the compressed air to form an explosive charge, a discharge valve in the duct leading from the explosion chamber to the working face of the rotor, means independent of the rotor to normally, yieldably close said valve, means independent of the rotor to hold said valve in open position at the instant of ignition, rotor driven means to release said holding means from the valve closing means after an explosion, and rotor driven means to open said air valve both prior and subsequent to an explosion and thereby cause a scavenging charge of compressed air to be discharged from the compressed air chamber and through the explosion chamber, said duct and to the working face of the rotor after an explosion.

3. In an internal combustion motor, a rotor, a stator, an explosion chamber, a duct

4
leading from the explosion chamber to the working face of the rotor, a discharge valve in said duct arranged to close against back pressure from the rotor, means independent of the rotor to normally yieldably close the valve and means independent of the rotor to hold the valve in open position at the instant of ignition, and rotor driven means to

release said holding means from the valve closing means.

In testimony whereof I affix my signature in presence of two witnesses.

FRANK L. GROVES.
